UNITED STATES PATENT OFFICE.

ETTORE S. MIRAGOLI, OF ST. LOUIS, MISSOURI.

FRESCO-WORK.

SPECIFICATION forming part of Letters Patent No. 311,509, dated February 3, 1885.

Application filed April 29, 1884. (No model.)

To all whom it may concern:

Be it known that I, ETTORE S. MIRAGOLI, of St. Louis, Missouri, have made a new and useful Improvement in Fresco-Work, of which 5 the following is a full, clear, and exact description, reference being had to the annexed drawings, making part of this specification, in which—

Figure 1 is a front elevation showing one 10 of the corner-pieces of the work; Fig. 2, a front elevation of one of the pieces used between the corner-pieces; Fig. 3, a cross-section, upon an enlarged scale, taken through any of the pieces; and Fig. 4, a view showing 15 the improvement applied to a wall or ceiling, a portion of the view showing the fastenings used in applying the work.

The same letters of reference denote the same parts.

20 This improvement consists in preparing surfaces in relief, suitably coloring them, and in finishing the surfaces in sections, so that the various sections can be readily made and handled, and so that they can be applied to 25 and combined upon the ceiling or wall in various ways, and so that, if desired, they can be removed from the ceiling or wall and re-applied elsewhere.

The improvement also relates to the construction of the surfaces.

30 In carrying out the improvement I take a sheet, A, of bibulous paper, suitably moisten it, and press it into a mold that is intagliated to correspond with the design to appear in relief upon the surface B.

It is desirable to press a second similar 40 sheet, C, of paper, into the mold against the first sheet, and perhaps a third, D, sheet against the second one, and in this respect I do not desire to be limited to any special number of sheets, so that when the surface B is prepared it shall have sufficient body and stiffness to be self-supporting when lifted at one edge.

45 To strengthen the surface, and at the same time obviate the need of employing so many sheets, A C D, in combination as to make the surface too heavy, a textile fabric, E, is

cemented or otherwise attached to the back of the rear sheet, D. The combined sheets 50 A C D E are then dipped in oil and dried, after which the front b of the surface is colored as desired, one color being applied, say, to the background b', and other colors to the relief b² of the surface. In thus preparing 55 the surface in relief this advantage is obtained: the outlines of the design are supplied to the workman, and the coloring in consequence can be readily applied and with less skill than upon a plain surface. Further, a better effect is produced by reason of portions of the surface being in relief.

B B' B', &c., represent the various sections of the surface. Fig. 4 illustrates one mode of applying them to a ceiling or wall, 65 F, the sections B B being the corner-pieces, and the sections B' B' being used to connect the corner-sections.

It is obvious that the sections can be placed as desired upon the ceiling or wall and relatively combined in many ways; also that in place of a textile fabric the sheets can be suitably otherwise strengthened.

The sections may be attached in place by means of tacks G, or by other suitable means.

I am aware that it is not new to make wallpaper of a roll of embossed sheets having a complete design stamped on them.

I am also aware that ceilings and walls have been ornamented with tiles made of 80 stamped glass, also with sheet metal, and also with designs in plaster. I am not, however, aware that walls and ceilings have been ornamented by making up the desired design of various stiff embossed paper-sections, each 85 section being removable from its place in the wall at will, and constructed as described and shown.

I claim—

1. The fresco-work herein described, consisting of sheets A, C, D, and E, dipped in oil, substantially as described.

2. A fresco for a wall or ceiling composed of various removable sections grouped together to form an ornamental design, each 95 section being made of one or more layers of

paper having its portion of the complete design stamped in relief, and stiffened and strengthened, substantially as described.

3. As a new article of manufacture, a fresco for walls or ceilings composed of separate and removable sections B, B', &c., of paper or analogous material stamped in relief and grouped together to form an ornamental design.

4. Fresco-work having a surface stamped to into relief and backed with textile fabric, and dipped in oil.

ETTORE S. MIRAGOLI.
